SPRAY NOZZLE WITH PRESSURE OPERATED CLEAN OUT

Filed March 19, 1949

UNITED STATES PATENT OFFICE

2,614,885

SPRAY NOZZLE WITH PRESSURE OPERATED
CLEAN OUTWilliam J. Roell and Thomas O. Berreau,
Minneapolis, Minn.

Application March 19, 1949, Serial No. 82,392

4 Claims. (Cl. 299—59)

1

This invention relates to spray nozzles with pressure operated clean outs.

It is the general object of the invention to provide a novel and improved spray nozzle including a needle which can be moved in and out of the outlet orifice of the nozzle to clean the same and means for operating said needle through a pressure differential that can be controlled at a point remote from the nozzle.

Another object is to provide a spray nozzle of cheap and inexpensive construction including a clean out needle for the spray orifice that can be operated by fluid pressure to clean the nozzle as the supply of fluid to the nozzle is temporarily cut off.

A further object is to provide spraying equipment including spray nozzles which can be cleaned rapidly when the spraying equipment is in use without removing the nozzles or portions thereof from the spraying equipment.

The objects and advantages of the invention will more fully appear from the following description made in connection with the accompanying drawing wherein like reference characters refer to the same or similar parts throughout the various views, and in which:

Fig. 1 is a view more or less diagrammatically illustrating spraying equipment embodying the invention; and

Fig. 2 is a vertical section taken through the spray bar substantially on the line 2—2 of Fig. 1 as indicated by the arrows.

There is shown a tank 3 which will contain the liquid to be sprayed and from this tank a pipe 4 runs to the intake of a suitable pump 5. From the outlet of the pump 5 a pipe 6 connects by a T fitting 7 to a pipe 8 connected to a control valve 9. The control valve 9 is in turn connected to another pipe 10 forming a spray bar. Connected to the T fitting 7 is a pipe 13 running to a three-way fitting 14, and this fitting 14 is in turn connected to a return line 15 running back to the tank 3. The return line 15 is provided with a regulating valve 16 and a pressure gauge 17 may, if desired, also be connected to this return line 15. The remaining connection of the three-way fitting 14 is connected to a branch line 18, the major portion of which is disposed in spaced parallel relation relative to the spray bar 10. Connected both to the spray bar and to the branch line 18 are a number of spray nozzles, each of which is designated as an entirety by the letter N.

Each spray nozzle N includes a body 19 having a central apertured cross web 20 dividing

the body into an upper cylindrical chamber 21, which will be designated a pressure chamber, and a lower chamber 22, which will be designated a spray supply chamber. The upper pressure chamber is closed by a connecting fitting 23 having internal screw threads which engage with external screw threads formed on the upper portion of the body 19. This fitting 23 has a central inlet opening 24 forming a fluid inlet port and the fitting 23 is also provided with inner shoulders 25 which project inwardly relative to the cylindrical chamber 21. The branch line 18 is connected by a nipple 26 to each port 24. The body 19 also has an intake port 27 which leads into the spray supply chamber and an L-shaped nipple 28 connects the main spray bar 10 to the port 27 of each spray nozzle.

Fitting within the lower part of the body 19 and received partially within the spray supply chamber 22 is a spray orifice member 29 having a small orifice 30 through which the fluid is adapted to be sprayed. Immediately above the orifice 30 the member 29 is provided with an upwardly diverging walled portion 31 and preferably the extreme upper edge of the member 29 is beveled as shown. The orifice member 29 has an external flange 32 which is held in sealed abutment with the lower end of the body 19 by a collar 33 having an internal thread connected to an externally threaded portion near the lower end of the body 19.

Fitting within the pressure chamber 21 of the nozzle is a piston 34 carrying a stem 35 which projects downwardly through the opening in the web 20 of the body. The stem 35 is of truncated conical shape at its lower end and it carries a needle 36 adapted for cooperative action with the orifice 30 upon reciprocation of the stem 35 to project in and out of the orifice 30. In other words, the needle 36 is aligned with the orifice 30 and on the extreme down movement of the piston 34 this needle is adapted to work into the orifice 30 and to punch out any dirt or foreign matter which may tend to clog the orifice. The conical portion 31 of the orifice member 29 immediately above the orifice 30 tends to guide the needle 36 into the orifice in case there is any tendency for the needle to be out of alignment with the orifice. A light coiled pressure spring 37 surrounds the stem 35 and bears at one end against the lower side of the piston 34 and at its other end against the cross web 20 of the body 19.

The opening in the cross web 20 through which

the stem 35 projects is made large enough so that there can be free communication between the two chambers 22 and 21 or, if desired, a small channel 38 may be cut in the web 20 at one side of the opening therethrough so as to assure such communication.

The valve 9 will preferably be a quick-acting valve and will be located at a position convenient to the operator of the spraying equipment. Thus, if the spraying equipment is mounted on a tractor and is being employed for agricultural spraying, the valve 9 will preferably be located near the seat of the tractor so that the valve 9 can be controlled by the tractor operator without getting off the seat.

In use, the pump 5 will draw the spray liquid from the tank 3 and force it through the pipe 6, T fitting 7, and pipe 8 and valve 9 which is normally open, into the spray bar 10 and the fluid will be forced through the nipples 28 into the various spray supply chambers 22 of the different valves N. The liquid will be ejected through the orifice 30 of the orifice members 29 in the usual fashion. Some of the fluid being pumped by the pump 5 will be forced through the bypass line 13 and return line 15 back to the tank 3, and by regulating the valve 16 and by observing the pressure gauge 17 it will be possible to regulate the pressure of the fluid being supplied to the various spray supply chambers 22 of the spray nozzles. As the pipe 18 which communicates through the three-way fitting 14 with the return line 13 communicates through the various nipples 26 with the pressure chambers 21 of the various spray nozzles above the pistons 34, the pressure above the pistons will be equalized by the pressure below the pistons and the springs 37 accordingly will hold the pistons in raised condition. In this connection, it has been before noted that the spray supply chambers 22 are in communication with the lower portions of the pressure chambers 21 below the pistons 34 and it will thus be readily understood that the fluid pressure above and below the pistons 34 will be balanced while the valve 9 is open. Let us assume that as is often the case some of the solid matter in the fluid being sprayed temporarily clogs one or more of the orifices 30 in the various nozzles N. It is a very simple matter to unclog these orifices by merely operating the valve 9 to close off the supply of fluid from the spray bar 10 to the various spray supply chambers 22 of the different nozzles. As the valve 9 is closed the fluid pressure within the spray supply chambers 22 and, accordingly, below the pistons 34 in the pressure chambers 21 is reduced relative to the fluid pressure in the pressure chambers 21 above the pistons 34. Accordingly, the pistons 34 will be forced downwardly against the tension of the springs 37, thereby causing the stems 35 and needles 36 to move downwardly to carry the needles 36 into the orifices 30 to punch out any accumulated dirt that may be in these orifices. The action takes place very fast and it is possible to temporarily close the valve 9 and immediately open it causing the unclogging of the various nozzles N almost instantaneously without skipping any substantial part of the area over which the sprayer travels. If the spraying equipment is mounted as on a tractor and the valve 9 is located adjacent the driver's seat, the unclogging of the nozzles can be very easily accomplished without the driver stopping the tractor and without necessitating the driver's leaving his seat.

Of course, as the valve 9 after being closed is

again opened, the pressure below and above the pistons 34 equalizes and the springs 37 thus force the pistons upwardly to return the needles 36 to their original position.

5 It will be seen that a simple but highly effective nozzle construction has been provided which will permit the cleaning of the outlet orifice of the nozzle through a differential in pressure that may be created in the different portions of the nozzle. It will also be seen that a novel spray bar construction has been provided which will permit ready cleaning of the nozzle without detachment of parts of the nozzle.

10 While in the illustrated nozzle a piston is provided which will be operated by the differential in pressure, it will, of course, be understood that other pressure operated mechanism may be employed for reciprocating the clean out needle whenever desired.

15 It will also be understood that various other changes may be made in the form, details, arrangement and proportions of the various parts without departure from the scope of the present invention which, generally stated, consists in the matter shown, and described, and set forth in the appended claims.

20 What is claimed is:

1. A spray nozzle comprising a body having an apertured cross web dividing the same into a pressure chamber and a spray supply chamber, both of said chambers having fluid admission ports, said spray supply chamber having a spray outlet orifice, a reciprocating piston working within said pressure chamber between said ports, a needle equipped stem connected to said piston and projecting through the aperture of said web, the needle of which stem is aligned with said spray orifice and resilient means urging said piston to move the needle of said needle equipped

25 stem out of said orifice.

2. A spray nozzle comprising a body having an apertured cross web dividing the same into a pressure chamber and a spray supply chamber, a piston working within said pressure chamber, a stem connected to said piston projecting through the aperture of said cross web and running into said spray supply chamber, a needle carried by said stem, said spray supply chamber having a spray orifice aligned with said needle, a spring reacting between said piston and said cross web and urging said needle out of said orifice, said pressure chamber having a fluid supply inlet port at the opposite side of said piston from said cross web and said spray supply chamber having a fluid inlet port.

3. A spray bar comprising a fluid supply line, a branch line running therefrom, a spray nozzle having in communication first and second chambers, said nozzle having a spray orifice in said first chamber and both of said chambers having fluid inlets, said fluid supply line being connected to the fluid inlet in said first chamber and said branch line being connected to the fluid inlet in said second chamber, a valve in said supply line for closing off the supply of fluid to said first chamber while permitting the supply of fluid through said branch line to said second chamber, pressure actuated means located in said second chamber, a needle operated by said pressure actuated means and moveable into and out of said orifice and resilient means acting to urge said needle out of said orifice whereby when said valve is open and the pressure is equalized in said two chambers said resilient means will hold said

75 needle out of said orifice and when said valve is

closed and the pressure in said second chamber exceeds the combined pressure of said resilient means and the pressure in said first chamber said needle will be urged against the tension of the said resilient means into said orifice.

4. A spray nozzle comprising a body having a first chamber having an inlet and a second chamber having an inlet and communicating with said first chamber, a spray outlet orifice in said first chamber, a clean out needle mounted for reciprocation in said body for projection into and out of said outlet orifice, a piston working in said body between said inlets in said two chambers and connected to said needle and adapted to actuate said needle to move the same into said orifice when the pressure in said second chamber exceeds substantially the pressure in said first chamber, and resilient means acting in conjunc-

tion with said piston for moving said needle out of said orifice as the pressure in said first chamber equals or exceeds the pressure in said second chamber.
